UNITED STATES PATENT OFFICE.

GILBERT K. INGRAHAM AND JOHN L. CRIST, OF SAN FRANCISCO, CALIFORNIA.

FLUID CAN OR BARREL HOLDER.

SPECIFICATION forming part of Letters Patent No. 364,351, dated June 7, 1887.

Application filed January 10, 1887. Serial No. 223,970. (No model.)

To all whom it may concern:

Be it known that we, GILBERT K. INGRAHAM and JOHN L. CRIST, residents of the city and county of San Francisco, State of California, have jointly invented an Improved Can or Barrel Holder; and we hereby declare that the following is a full, clear, and exact description of the same, reference being had to the accompanying drawings.

10 Our invention relates to an improved manner of suspending in a frame a can or barrel containing a fluid, for the purpose of decanting the same.

The following description fully explains the nature of our said invention and the manner in which we proceed to construct, apply, and use the same, the accompanying drawings being referred to by figures and letters.

Figure 1 is a perspective view of the device, showing the can tilted and held in position. Fig. 2 is a plan of the same, showing a spring-pawl attached to the frame. Fig. 3 is a vertical section through the frame, showing the ratchet-bar and the manner of suspending the can.

Referring to Fig. 1, *a* is the frame, which may be made of wood or metal, having the floor or bottom cut away, as shown at *b*, to afford facility in decanting the fluid. We 30 make the frame of a suitable size to hold either a can or a barrel. For the purpose of holding the can in position at any required angle, we attach to the inclined edge of the frame a pawl, *k*, which is thrown by hand into a ratchet-bar, Fig. 1; or we accomplish the same thing 35 by attaching a spring pawl, *l*, in a similar position on the side of the frame, Fig. 2.

The can *c*, provided with a discharge hole, *d*, and a handle, *e*, such as is commonly used to 40 hold oil or other fluid, is suspended on the frame by means of a holder or cage made of iron bands or straps *f g*. The band *g* extends across the bottom of the can and up both sides, and is secured to the band *f*, which extends

horizontally around the center of the can. The 45 band *g* may extend up all sides of the can. One end of the band *g* is riveted to the center of a semicircular ratchet-bar, *i*, and on the opposite side the other end of band *g* extends above the horizontal band *f*, and is pivoted on 50 the bolt *h*. The ends of the ratchet-bar are riveted to the band *f*, and secured to this band *f* above the ratchet-bar is a short band or ear, *m*, which is pivoted on the opposite bolt, *h*, Figs. 1, 3. The can is placed in this holder 55 and may be readily removed and replaced by another.

For the purpose of holding a can in position while decanting its contents, we preferably employ only one ratchet-bar; but we do not 60 confine ourselves to this arrangement, as in suspending a barrel in the holder, or even a can, we may use a ratchet bar and pawl on each side.

In decanting a fluid from a can or a barrel 65 the vessel is tilted to the proper angle and the pawl *k* is thrown by hand into the ratchet-bar *i*; or if a spring-pawl *l* is used, it is held by hand until the vessel is properly tilted, when 70 it is left free to engage with the ratchet-bar, by which the vessel is held in the required position. In order to facilitate the discharge, the bottom or floor of the holder is cut away to adapt it to the form and size of the receiver.

Having thus fully described our invention, 75 what we claim, and desire to secure by Letters Patent, is—

The combination of the ratchet-bar *i*, which is secured to the holder in the manner described, with the holder consisting of iron bands *f g*, 80 and the frame *a*, having pivot-bolts *h*, and a pawl, *k*, or a spring-pawl, *l*, secured thereon, substantially as and for the purpose set forth.

GILBERT K. INGRAHAM. [L.S.]

JOHN L. CRIST. [L.S.]
